SERVICE RIBBON BAR

Jerome M. Hilborn, Bronxville, N. Y., assignor to
 Hilborn-Hamburger, Inc., New York, N. Y., a
 corporation of New York

Application September 23, 1944, Serial No. 555,550

4 Claims. (Cl. 40—1.5)

1

This invention relates to service ribbon bars.

An object of this invention is to provide a service ribbon bar of the character described having highly improved means for clamping the ribbon to the bar, said clamping means being so constructed that the ribbon can easily be removed or replaced.

Yet a further object of this invention is to provide a service ribbon bar of the character described on which a plurality of ribbons may be mounted, each of said ribbons being easily separately removable and replaceable.

Still a further object of this invention is to provide a compact, neat and durable service ribbon bar of the character described, which shall be relatively inexpensive to manufacture, easy to attach to a garment, and which shall yet be attractive in appearance, and practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention:

Fig. 1 is a front elevational view of a service ribbon bar embodying the invention.

Fig. 2 is a cross-sectional view taken on line 2—2 of Fig. 1.

Fig. 3 is a perspective view of the ribbon holder forming part of the service ribbon bar shown in Fig. 1.

Fig. 4 is a perspective view of the clamp plate forming part of the service ribbon bar shown in Fig. 1.

Fig. 5 is a front elevational view of a service ribbon bar embodying the invention as utilized for supporting a plurality of individual ribbons.

Fig. 6 is a top edge view thereof.

Fig. 7 is a rear view thereof.

Fig. 8 is a rear view of three separate ribbon holders end to end, which may be mounted on a single service clamp plate.

Fig. 9 is a rear view of the plate clamp forming part of the service ribbon bar shown in Fig. 5.

Referring now in detail to the drawing, 10 designates a service ribbon bar embodying the invention. The same comprises a ribbon holder 11 on which the service ribbon 12 is mounted, and a

2

clamp plate 13 for clamping the ribbon to the ribbon holder.

The ribbon holder 11 may be made of sheet metal, and comprises a channel-shaped member 5 having a web 15 and parallel top and bottom flanges 16. The web 15 may be formed with a cutout or opening 17 to reduce its weight, and flanges 16 are formed with aligned, narrow, longitudinal, central slots 18 adjacent the web 15. The slots 18 are short relative to the length of the holder 11 as shown in Fig. 3 of the drawing. The ribbon 12 has a portion 12a covering the front surface of web 15, portions 12b covering the outer surface of flanges 16, portions 12c covering the inner surfaces of flanges 16, and portions 12d contacting part of the inner surface of the web 15. The holder 11 is of substantially the same length as the width of the ribbon and, as shown in Fig. 2 of the drawing, the ribbon is drawn around the edges 16a of flanges 16.

The service ribbon is clamped in place on the holder 11 by means of the clamp plate 13. Said plate may also be made of sheet metal. It is substantially rectangular in shape and adapted to fit 20 into the channel-shaped holder 11. Clamp plate 13 is substantially as long as holder 11 and may be formed with a central cutout or opening 20 to reduce its weight. It is furthermore formed with a pair of outwardly projecting, central lugs 21 on the upper and lower longitudinal edges 13a thereof. The width of the plate 13 is such as to nicely fit within the holder, allowing for the thickness of the ribbon, and engage the service ribbon to hold portions 12c of the ribbon against the inner surfaces of the flanges 16.

The clamp plate also holds portions 12d of the service ribbon against the inner surface of web 15; the projections or lugs 21 bulge portions of the ribbon into slots 18, thereby firmly clamping the ribbon in taut condition on the ribbon holder 11. The clamp plate 13 may be provided with a pivoted attaching pin 25 for pinning the bar 10 to a garment. Any other suitable means may be provided on clamping plate 13 to attach 35 the bar to a garment.

In Figs. 5 to 9, there is shown a service bar pin 10a embodying the invention and illustrating a modified construction. The bar pin 10a is for mounting a plurality of ribbons in tandem. The 40 bar pin 10a comprises an elongated clamp plate 30, the length of which is a multiple of the length of a single ribbon; thus, it may be either two, three or four times as long as a single clamp plate 13. It may be formed with a plurality of 45 longitudinal slots 31, each one centralized with

respect to the length of a single ribbon. The clamp plate 30 is also formed in the upper and lower edges thereof with outwardly projecting pairs of lugs 32 centralized relative to the slots 31. Fitted on the plate 30 are a plurality of holders 11 in tandem, with ribbons 12 thereon. Thus in the drawing, the service ribbon bar 10a is for mounting three ribbons, and hence three ribbon holders, each with a ribbon thereon, may be mounted on the one clamp plate. The ribbon holders are separately removable for replacing the ribbons.

The clamp plate 30 may be provided with any suitable means for attaching the same to a garment. In the drawing, plate 30 is shown to be provided at the ends thereof with rearwardly projecting pins 35 which may pierce the garment and receive pin locks thereon. It will be noted that each pair of projections 32 may bulge a ribbon into a pair of slots 18 on one of the ribbon holders 11.

To remove a ribbon holder, it is but necessary to press up on one flange 16 of the holder, and swing the holder out about its lower flange. The flanges are resilient and hence removal or mounting of the holders is easily accomplished.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, what I claim as new and desire to secure by Letters Patent, is:

1. A service ribbon bar comprising a channel-shaped ribbon holder having a web portion and parallel flanges extending substantially at right angles from said web portion, said flanges being formed with openings, and a clamp plate removably fitted between said flanges, and formed with projections adapted to urge into said openings portions of ribbon on said ribbon holder, said holder being of substantially the same length as said clamp plate, and means on the clamp plate for attaching the same to a garment.

2. In combination, a channel-shaped ribbon holder having a web portion, and parallel flanges extending substantially at right angles from said web portion, said flanges being formed with openings, a ribbon contacting the outer surface of the web and being folded over the outer surfaces of the flanges and around the edges of the flanges and contacting the inner surfaces of said flanges and the inner surface of said web, and a removable clamp plate within said ribbon holder, and

between the flanges thereof, said clamp plate having projections on the longitudinal edges thereof pressing portions of the ribbon into the openings in said flanges.

3. In combination, a channel-shaped ribbon holder having a web portion, and parallel flanges extending substantially at right angles from said web portion, said flanges being formed with openings, a ribbon contacting the outer surface of the web and being folded over the outer surfaces of the flanges and around the edges of the flanges and contacting the inner surfaces of said flanges and the inner surface of said web, a removable clamp plate within said ribbon holder, and between the flanges thereof, said clamp plate having projections on the longitudinal edges thereof pressing portions of the ribbon into the openings in said flanges, said openings being located adjacent the web portion of the holder, and said clamp plate being adapted to press portions of the ribbon against the inner surface of the web, and against the inner surfaces of said flanges.

4. A multiple service ribbon bar comprising an elongated clamp plate having on its longitudinal edges spaced pairs of opposite projections, ribbon holders removably secured on said clamp plate in tandem, said ribbon holders each being channel shaped, and having a web portion and yielding parallel flanges extending substantially at right angles from said web portion, said flanges being formed with longitudinal slots adjacent the web, each pair of lugs on the clamp plate projecting into a pair of slots in one of the holders, and a ribbon on each holder covering the front face of the web and folded around the flanges and contacting the inner surface of the web, and said lug serving to press portions of the ribbon into said slots.

JEROME M. HILBORN.
